PHOTOGRAPHIC DEVELOPER

Augustin J. Powers, Jr., Old Brookville, and George Schwarz, Glen Head, N.Y., assignors to Powers Chemical Co., Inc., Glen Cove, N.Y., a corporation of New York
No Drawing. Filed June 26, 1962, Ser. No. 205,215
6 Claims. (Cl. 96—66)

The invention relates to a novel and improved process for reenergizing formaldehyde - bisulfite - hydroquinone developers such as are used for the development of high contrast photographic film in the graphic arts, which developers are sometimes referred to briefly as "litho developers."

Developers of this general kind are well known in the graphic arts and varieties of them are known in the trade as "Chemco Powerlith" developer, "Kodak D-85," and others are described in some detail in the prior patents to Donovan and Wadman No. 2,313,523, Blake No. 2,533,990, Welliver and Krizka No. 2,902,367, Henn and Goffe No. 3,030,209, and Du Pont British Patent No. 643,411.

All of the prior litho developers have a relatively low capacity and begin to show substantial exhaustion after the development of a relatively small amount of litho-film, and are discarded in commercial practice, due to the poor quality of negatives which are produced after only a selectively small quantity of film has been developed.

Additionally, in the development of litho-type emulsions in formaldehyde-bisulfite developers "pepper spots" often develop, as reported by Yule, in Journal of the Franklin Institute, March 1945, pages 221 to 230. It has now been found that such pepper spots often become prevalent when such developers are prepared from concentrated solutions which include an alcohol, such as ethyl alcohol, diethylene glycol or monomethyl ether of ethylene glycol; and the developing process and reenergizer of the present invention are not limited to such alcohol-containing developers, but extend the useful life of formaldehyde bisulfite developers in general.

Conventional replenishers for photographic developers, including high contrast developers, generally comprise a substantial quantity of a developing agent, such as hydroquinone; enough sulfite, such as sodium sulfite, to prevent aerial oxidation of the developing agent; and an alkaline material, such as sodium hydroxide or carbonate, sufficient to restore the partially exhausted developer bath to approximately its original activity. A relatively small amount of such a replenisher is added to the partially exhausted developer bath, after which the bath may be used for some further quantity of film.

According to the present invention, the surprising result has been found that an infectious developer bath (consisting essentially of a water solution of hydroquinone as the sole developing agent, carbonyl-alkali metal bisulfite, preferably formaldehyde-alkali metal bisulfite, alkali metal hydroxide, carbonate or borate and a restrainer such as potassium bromide) which soon begins to show signs of exhaustion after the development of only a relatively small amount of silver halide photographic film, such as litho-film, may be substantially restored to its original activity and will produce film negatives of excellent quality, by reenergizing the developer bath, using only a small amount of solution consisting essentially of an alkali metal sulfite and a relatively small amount of an alkali metal hydroxide, which solution in relatively small quantities, is added to the partially exhausted developer bath.

Using the reenergizer of the present invention, the infectious developer bath, after it has been partially exhausted and would normally be discarded, may be reenergized and restored to substantially its original activity

2

by mixing with it a small amount of the reenergizer, and the capacity of the developer bath may be increased to as much as 3, 4 or more times its normal capacity.

The present invention has for its object the provision of a novel and improved method of reenergizing and greatly extending the useful life of an infectious developer bath. A further object is the provision of a novel and improved reenergizing solution for partially exhausted infectious developer baths. Another object is the provision of a novel and improved method of preventing undesired spots when using formaldehyde-bisulfite developers which include an alcohol in their composition. Still another object is the provision of a novel and improved reenergizing solution by which an infectious developing bath may be maintained at good working standards over a greatly extended film capacity, thereby resulting in greater economy and more uniform developed negatives.

It has now been found baths of litho developers may be reenergized after their normal useful life by adding to them small amounts of a concentrated aqueous solution of a sulfite ion and an alkali. Preferably, such a concentrated solution comprises sulfite ions, hydroxyl ions and one or more alkali metal ions, such as sodium and potassium. A mixture of different alkali metal ions are preferred so that the reenergizing solution may be more concentrated, although either sodium or potassium ions alone may be employed.

Thus, broadly, the reenergizing solution consists of sodium or potassium sulfite or bisulfite and sodium or potassium hydroxide or carbonate, preferably sodium, potassium, sulfite and hydroxide ions. This may be provided by a concentrated water solution of sodium sulfite and potassium hydroxide, such solution being as concentrated as can be reliably stored and shipped without crystallization.

Typical of the formaldehyde-bisulfite developers which may be used in the process of the present invention are those compounded within the ranges of the following general formula:

40	Hydroquinone	grams	6 to 25
	Formaldehyde-alkali metal bisulfite	do	20 to 60
	Alkali metal hydroxide	do	9.5 to 10.5
	(Or alkali metal carbonate)	do	20 to 95
45	Boric acid	do	5 to 25
	(Or alkali metal borate)	do	8 to 35
	Restrainer (alkali metal bromide)	do	0.5 to 10.0
	Sequestering agent, such as ethylene-diamine tetraacetic acid	grams	0.0 to 1.0
50	Hydroquinone solvent, such as methyl alcohol, ethyl alcohol, methyl or ethyl monoether of ethylene glycol, diethylene glycol or triethylene glycol	ml.	0.0 to 250
	Sodium sulfite or bisulfite	grams	0 to 5.0
55	Water to make 1.0 liter.		

The quantity of the alkali used is chosen so that a pH range between 9.8 and 10.8 is obtained.

Reenergizers, according to the present invention, for such litho developers consist essentially of a concentrated water solution of sodium and potassium ions and of hydroxyl ions and sulfite ions, and are preferably composed of sodium or potassium hydroxide or carbonate and/or borate and sodium or potassium sulfite or bisulfite, the alkali metal ions preferably being mixed. Such a solution may consist of:

Sodium or potassium sulfite	grams	100 to 250
Sodium or potassium hydroxide	do	20 to 80
Water to make 1 liter.		

In the method of the present invention from 5 to 40 cc. of the reenergizing solution is added to each liter of partially exhausted litho developer bath, to restore the

bath to substantially its original speed and activity. Thus, such additions comprise from 0.5 to 10 grams of sodium or potassium sulfite, combined with from 0.1 to 3.2 grams of sodium or potassium hydroxide, in a relatively concentrated aqueous solution, comprising sufficient water to form from 5 to 40 cc. of aqueous solution. This reenergizing of the bath may continue until the capacity of the bath has been extended even to as much as 3, 4 or more times the capacity of the bath with such novel reenergization.

Typical of the infectious developers which are usually reenergized by the method of the present invention are the following; with respect to each of which the preferred reenergizer solution and its manner of use is specified:

Example 1

Solution A:

Formaldehyde potassium bisulfite monohydrate	grams	110	
Hydroquinone	do	135	20
Potassium hydroxide 45% water solution	ml	2.8	
Diethylene glycol	ml	118	
Ethylene diamine tetracetic acid	grams	0.26	25
Water to make 1000 ml.			

Solution B:

Formaldehyde potassium bisulfite	grams	63	
Boric acid	do	13.5	
Potassium bromide	do	1.57	30
Sodium hydroxide	do	9.50	
Water to make 1 liter.			

Preferably, equal parts A and B are mixed and diluted with 4 parts of water to make six liters of working developer for development of litho film.

Replenisher (Solution C):

Sodium sulfite	116 grams	440 grams	
Potassium hydroxide 45% water solution	256 ml	965 ml	
Water to make	1 liter	1 U.S. Gallon	

As the working developer begins to show signs of exhaustion, 30 to 240 cc. preferably about 90 cc. of the replenisher per six liters of working developer are added and thoroughly mixed, whereby the working developer regains substantially its initial activity. Several such replenishing additions may be made before the bath is exhausted and ready to be discarded.

However, when developing certain types of film, such as "Kodak Litho film Type III" as presently sold, best results are obtained with it if about 10 ml. per liter of replenisher is added before the first film is developed.

Example 2

Solution A:

Hydroquinone	grams	40	
Potassium formaldehyde bisulfite monohydrate	do	345	
Ethyl alcohol	cc	80	
Water sufficient to make 1 liter.			60

Solution B:

Potassium borate (anhydrous)	grams	160	
Potassium carbonate sesquihydrate	do	204	
Potassium bromide	do	11.0	
Water sufficient to make 1 liter.			65

For use one part of solution A and one part of solution B are mixed and diluted with 3 to 5 volumes of water based on the total volume of A and B solutions to make the working solution for development of litho film.

This developer bath may be reenergized several times

75

by the addition to the bath of 5 to 40 cc. per liter of a replenishing solution consisting of:

Potassium sulfite crystalline	grams	220
Sodium hydroxide	do	66
In water solution	liters	1

or alternatively, a solution comprising:

Sodium sulfite anhydrous	grams	144
Potassium hydroxide	do	92
Water to make 1 liter.		10

or most preferably a water solution of:

Sodium bisulfite	grams	120
Potassium hydroxide	do	167
Water to make 1 liter.		15

Example 3

Solution A:

Potassium formaldehyde bisulfite monohydrate	grams	270
Hydroquinone	do	100
Sodium bisulfite, anhydrous	do	21
Ethyl alcohol 95%	ml	190
Water to make 1 liter.		

Solution B:

Potassium carbonate, sesquihydrate	grams	340
Boric acid crystals	do	55
Potassium bromide	do	5
Water to make 1 liter.		

For use one part of A is mixed with six parts of water and with one part of B to make a working developer.

The reenergizer may comprise:

Solution C:

Sodium sulfite, anhydrous	grams	144
Potassium hydroxide	do	92
Water to make 1 liter.		

From about 5 to 50 ml. of reenergizer per liter of developer are used to reenergize the developer and may be repeated several times.

Example 4

Solution A:

Formaldehyde sodium bisulfite	grams	158
Hydroquinone	do	135
Potassium hydroxide	do	24
Methyl ether of ethylene glycol	ml	100
Water sufficient to make 1 liter.		

Solution B:

Borax (Na ₂ B ₄ O ₇ ·7H ₂ O)	grams	10
Sodium carbonate monohydrate	do	79
Sodium bromide	do	7
Sodium bisulfite	do	5
Water to make 1 liter.		

Solution C:

Sodium sulfite	grams	210
Sodium hydroxide	do	70
Water to make 1 liter.		

For use, one part of A and one part of B are added to two parts of water and mixed.

From about 10 to 25 ml. of replenisher are used per liter of working developer.

Example 5

Another example of a litho developer and its reenergizer according to the present invention is as follows:

Solution A:

Sodium bisulfite	grams	1.90
Formaldehyde sodium bisulfite	do	37.00
Boric acid	do	7.50
Hydroquinone	do	22.50
Potassium bromide	do	1.57

Solution B:

Sodium hydroxide	grams	9.50
Water to make 1000 ml.		

For use equal parts of solutions A and B are mixed, and may be reenergized by additions of the energizer solution C.

Reenergizer Solution C:

Water solution comprising—

Potassium sulfite anhydrous	grams	150
Potassium carbonate	do	150
Water to make 1 liter.		

Example 6

Still another infectious developer and its reenergizing solution have the following formulation:

Solution A:

Sodium bisulfite	grams	2.18
Acetaldehyde sodium bisulfite	do	46.9
Boric acid	do	8.5
Hydroquinone	do	25.6
Potassium bromide	do	1.78

Solution B:

Sodium hydroxide	grams	10.44
Water to make 1000 ml.		

For use, equal parts of solutions A and B are mixed and used.

Solution C:

Potassium sulfite	grams	100
Potassium carbonate	do	120
Water to make 1000 ml.		

Equal parts of solutions A and B are mixed for use.

When somewhat exhausted, the developer may be reenergized by adding 10 to 50 ml. of the Solution C per liter of developer, and may be repeated several times.

It should be understood that the reenergizing solutions are preferably highly concentrated but may be diluted, so long as the working developer is not seriously diluted by their addition. Thus a solution such as Solution C of Example 1 may be diluted with 5 parts of water and from 150 to 1200 ml. used for each six liters of partially used working developer. However, such dilution impairs the working developer, and for that reason, the reenergizer should be as concentrated as is practically possible.

The invention in its broader aspects is not limited to the specific steps, processes and compositions shown and described but departures may be made therefrom within the scope of the accompanying claims without departing from the principles of the invention and without sacrificing its chief advantages.

This application is a continuation-in-part of our prior co-pending application Serial No. 195,030, filed May 14, 1962.

What is claimed is:

1. A process for reenergizing and maintaining the activity of a hydroquinone containing carbonyl-bisulfite developer for lithographic film, the hydroquinone being the sole developing agent, which comprises adding to the developer, after some film has been developed therein, an aqueous solution consisting essentially of from 0.5 to 10 grams of an alkali metal sulfite and from 0.1 to 3.2 grams of an alkali metal hydroxide per liter of developer, the said aqueous solution being substantially free of hydroquinone and other organic developing agents.

2. A process for reenergizing and maintaining the activity of a hydroquinone containing carbonyl-bisulfite developer for lithographic film, the hydroquinone being the sole developing agent, which comprises periodically adding to the developer, per liter of developer, from about 5 to 50 cc. of an aqueous solution consisting essentially of from 100 to 250 grams per liter of an alkali metal sulfite and from 20 to 80 grams per liter of an alkali metal hydroxide, the said aqueous solution being substantially free of hydroquinone and other organic developing agents.

3. A process for reenergizing and extending the activity of a used hydroquinone-containing formaldehyde-alkali metal-bisulfite developer for lithographic film, the hydroquinone being the sole developing agent, which comprises periodically adding to the developer, per liter of developer, from about 5 to 50 cc. of aqueous solution consisting essentially of from 100 to 250 grams per liter of an alkali metal sulfite and from 20 to 80 grams per liter of an alkali metal hydroxide, the said aqueous solution being substantially free of hydroquinone and other organic developing agents.

4. A process as in claim 3 wherein the developer contains an alcohol.

5. A process as in claim 4 wherein the alcohol is selected from the group consisting of diethylene glycol and triethylene glycol.

6. A re-energizing solution for periodic addition to a carbonyl-alkali metal-bisulfite developer having hydroquinone as its sole developing agent consisting essentially of an aqueous solution of sulfite and hydroxyl ions and associated alkali metal ions selected from the group of

salts consisting of sodium and potassium sulfites in a quantity of from 100 to 250 grams per liter and sodium and potassium hydroxide of from 20 to 80 grams per liter.
